UNITED STATES PATENT OFFICE.

JOHN HARRIS, OF LAKEWOOD, OHIO, ASSIGNOR OF ONE-HALF TO JAMES R. ROSE, OF PITTSBURGH, PENNSYLVANIA.

GAGE.

1,291,497.

Specification of Letters Patent. Patented Jan. 14, 1919.

Application filed August 10, 1917. Serial No. 185,417.

To all whom it may concern:

Be it known that I, JOHN HARRIS, a citizen of the United States, residing at Lakewood, in the county of Cuyahoga and State 5 of Ohio, have invented a certain new and useful Improvement in Gages, of which the following is a full, clear, and exact description, reference being had to the accompanying drawings.

10 This invention relates to gages and more particularly to gages of the Bourdon type. It is the object of the invention to which this application is directed to reduce to a minimum the liability of injury to operators 15 and by-standers in the event that the tubes of such gages should be ruptured and the casings thereof broken through the access of gas thereto under a pressure greater than that which the casings are capable of withstanding.

20 In the drawings forming a part hereof Figure 1 represents a side elevation of the top of a gas tank having a gage of the Bourdon type connected to the pipe leading therefrom. Fig. 2 is a view, partly in section and partly in elevation, of the said gage, the cover being removed. Fig. 3 is 25 a detail in perspective of the blow-out member for the wall of the gage; and Fig. 4 a detail in perspective of the plug which 30 serves to control the admission of gases to the gage and to safeguard the Bourdon tube against rupture.

35 Describing by reference characters the various parts illustrated herein, 1 denotes the upper portion of a tank such as is used for the storage of gases under high pressure and 2 the valve controlling the supply of gas from the tank through a pipe 3. 4 denotes the cylindrical casing wall of the gage, said wall being provided with an opening in 40 the bottom thereof for the reception of the nipple 5. This nipple is provided with the usual head 6 by means of which it is secured 45 to the cylindrical wall 4, as by means of screws 7. 8 denotes the Bourdon tube which extends through the head 6 and connects with the bore 9 of the nipple. The lower 50 end of the nipple is threaded whereby it is secured to a connection 10 extending upwardly from the pipe 3.

55 The outer end of the tube 8 is connected by a curved extension 8^a and a link 10 with a curved extension 11^a of a gear segment 11, said segment meshing with a pinion 12

on a pointer shaft 13. A hair spring 14 is also connected to the pointer shaft and to the bracket 15 for the purpose of holding the said shaft and the pointer in the maximum indicating position in the event that the 60 pressure developed within the tube 8 is sufficient to disengage the gear and pinion. The parts thus far described are of usual construction.

65 Threaded into the bore 9 is a plug 16, said plug having a restricted passageway 17 therethrough and being provided with a head 18 spaced from said passageway and overhanging the discharge end thereof. The head 18 will preferably be of such size as to 70 fit within the bore 9 and provide an annular passageway between said head and the wall defining said bore. The plug may be provided with a slot 17^a for the reception of a screw driver or other instrument by which 75 it may be inserted into, withdrawn from, and adjusted along the bore 9. Communication between the bore 9 and tube 8 is effected by the passage 9^a, also preferably of restricted size, so that the pressure in the gage may 80 always rise slowly, thus conserving the integrity and accuracy of the mechanism.

85 The top of the cylindrical wall 4 is provided with an opening, indicated at 4^a. This opening is adapted to be closed by means of a plate 19 having an area sufficiently greater than the area of said opening to overlap the same. Secured to the lower central portion of the plate 19 is a flat spring 20, the spring and plate being shown as connected by a 90 rivet 21. This spring is preferably longer than the plate 19 and the opening 4^a and is shown as extending longitudinally of said plate. While the plate 19 is shown as rectangular in outline, I do not propose to 95 limit myself to such shape nor to the particular shape and arrangement of the spring 20. The plate 19 may be applied to the cylindrical casing wall 4 by flexing the ends of the spring toward each other so as to permit them to be inserted within the opening 4^a. The spring will then hold the plate seated over the opening 4^a.

100 In operating with gases, it sometimes happens that, through faulty manipulation, a high pressure is suddenly developed within 105 the pipe 3 and within the connections leading to the gage. With gages as ordinarily constructed, the gas under these conditions will strike a blow upon the metal of the 110

5 tube 8 which will frequently result in its
rupture or permanent injury. By using the
narrow passageway 17, the gas is prevented
from entering the tube 8 rapidly; further-
more, the head 18 acts as a baffle to prevent
a stream of gas under high pressure from
striking the tube suddenly. In other words,
the restricted passageway 17 and the baffle
head 18 prevent the rupturing or permanent
10 injury of the tube 8 through the develop-
ment of a high pressure in the pipe 3 lasting
for a comparatively short period. How-
ever, should excessive pressure be main-
tained for a considerable period of time and
15 result in rupturing the tube, the gage wall
4, being incapable of withstanding this pres-
sure, will also be ruptured, heretofore with
danger to the operator and the by-standers.
In my device upon the rupture of the tube
20 8, the plate 19 will be blown upwardly, thus
preserving the casing and because of its lo-
cation at the top of the gage, will not in-
jure any person who may be in the vicinity.

25 While the plug 16 is particularly advan-
tageous in connection with high-pressure
gases, its field of usefulness is not limited
to gases under such pressures. It will pre-
vent fluctuations of pressure in the tube
and consequent oscillation of the pointer in
30 connection with gages operating under pres-
sure of five pounds and less. This is par-
ticularly true where the gage is used in con-
nection with a reciprocating pressure or
charging pump.

35 The construction for ordinarily prevent-
ing the rupture or permanent injury of the
tube constitutes no part of the invention
which it is the purpose of this application to
secure; the same constituting the subject
40 matter of a separate application to be filed
hereafter.

Having thus described my invention what
I claim is:—

1. In a gage, the combination of a casing,
45 and a safety device in the upper portion of
said casing adapted to be removed by the
pressure of gas within said casing.

2. In a gage, the combination of a cylin-
drical casing having an opening in the upper
portion of the cylindrical wall thereof, a 50
plate for covering said opening, and yield-
ing means for holding said plate in oper-
ative relation to said opening.

3. In a gage, the combination of a cylin-
drical casing having an opening in the upper 55
portion of the cylindrical wall thereof, a
plate adapted to close said opening, and a
spring secured to said plate and adapted
to engage the inside of the casing at a plu-
rality of points thereby to normally retain 60
the plate in operative relation to said open-
ing.

4. In a gage, the combination of a cylin-
drical casing having an opening in the upper
portion of the cylindrical wall thereof, a 65
plate conforming to and of greater extent
than said opening whereby it may cover and
overlap the same, and a spring secured at
its central portion to the underside of said
plate, the ends of said spring being adapted 70
to engage the inside of the cylindrical casing
on opposite sides of the opening there-
through, whereby the plate will normally
be held in operative relation to said opening
by said spring.

5. In a gage, the combination of a cylin-
drical casing having an opening in the upper
portion of the cylindrical wall thereof, a
plate adapted to close said opening, and
means connected with said plate and yield- 80
ingly engaging the inside of the cylindrical
wall of the casing for holding said plate in
operative relation to said opening.

6. In a gage, the combination of a cylin-
drical casing having an opening in the upper 85
portion of the cylindrical wall thereof, a
plate adapted to cover and overlap said
opening, and a flat spring secured to and
having its ends diverging from the under
side of said plate and adapted to engage the 90
inside of the casing adjacent said opening.

In testimony whereof, I hereunto affix my
signature.

JOHN HARRIS.
